UNITED STATES PATENT OFFICE.

ALBA PARKER SMITH, JR., OF BROCKTON, MASSACHUSETTS, ASSIGNOR
TO ARTHUR A. MAXWELL, TRUSTEE, OF BOSTON, MASSACHUSETTS.

AUTOMATIC VEHICLE-FENDER.

No. 836,283.

Specification of Letters Patent.

Patented Nov. 20, 1906.

Application filed December 13, 1905. Serial No. 291,528.

To all whom it may concern:

Be it known that I, ALBA PARKER SMITH, Jr., a citizen of the United States, residing at Brockton, in the county of Plymouth and 5 Commonwealth of Massachusetts, have invented an Improvement in Automatic Vehicle-Fenders, of which the following description, in connection with the accompanying drawings, is a specification, like letters and 10 figures on the drawing representing like parts.

My invention relates to automatic fenders particularly adapted for use in street-railway cars, though equally applicable to all classes 15 of vehicles.

The features of my invention will be best understood by reference to the following description, when taken in connection with the accompanying drawing of one embodiment of 20 my invention selected for the purpose of illustration, while its scope will be more particularly pointed out in the appended claims.

The figure shows an elevation of the right side of a car-platform and the fender attached thereto.

The structure of the platform and fender being alike on both sides, but one side is shown and described to avoid duplication.

As herein shown, the car-platform A is provided with a framework comprising depending front and rear supports or hangers 1 2, connected by a suitable brace 3, and said supports are secured to a transverse beam or bolster 4 5, connecting with the supports on 35 the opposite side of the car.

A fender-carrier 6 is pivoted at 7 to and adjacent the lower end of each front hanger 1 and is formed with bearings carrying rollers or other studs 8 to support the adjacent side 40 arm 9 of the fender and to enable it to be moved or slid lengthwise of the car from its front or operative position into the position indicated by dotted lines *a a* when not desired for use. The inner end of this arm has 45 a hook end 10 to engage a cross-bar 11, secured to the rear hangers and to hold the fender in said operative position longitudinally, and yieldingly to maintain the carrier in a horizontal position with the fender elevated a spring 12 is interposed between the bolster 5 and said fender-arm. The outer end of the fender-arm is turned down, so as to be normally carried a few inches above the ground, and adjacent to said end is a de-

pending bracket 13, carrying a roller 14, preferably of wood, adapted to run upon the ground or track when the fender is depressed. The front of the fender is provided with a yielding buffer 15 to prevent injury to the person or object struck thereby in collision. 55 The pivoted carrier is also provided with a stop or projecting arm 16, pivoted to the carrier at 17 above said side arm and curved outwardly, so that its free end bears upon the side arm to prevent any inward motion or 60 sliding of the fender-arm therein, it being apparent that to slide the fender inwardly with the stop in its normal position said stop will swing downwardly to bind or lock against said arm to prevent its inward motion. This 65 arrangement prevents inward motion of said fender from any outer position into which it may be drawn or carried, an additional stop 16^a being provided on the fender-arms for holding it in the outer or operative position 70 in which it is normally carried.

When slid outwardly into operative position, the fender is yieldingly held in a horizontal position by means of said spring and is prevented from being lifted by the engagement of the cross-bar with the hooked ends of the side arms. The depression of the fender and carrier, however, is only limited by the contact of the roller with the track or ground, which brings the front of the fender 80 and its attached buffer so close to the ground as to prevent objects of any size from slipping thereunder. (See dotted lines *d*.)

In operation the front of the fender is carried at such a height from the ground as to 85 upset or trip a person that is struck thereby to cause him to fall on the fender, and said fender by being pivoted as described is automatically and immediately depressed upon striking any obstacle, acting as a scoop to 90 pick it up or throw it onto the fender. In case, however, the obstacle is not picked up by the scooping action of the fender it prevents the latter from moving forward without sliding or rolling said obstacle with it, and 95 as the fender is pivoted by its carrier to permit only inward swinging thereof it is depressed automatically the instant it strikes any obstacle in its path without the aid of the motorman or operator. In either case 100 the fender acts to prevent said obstacle or person from getting under the fender to be run over by the car or vehicle. Said fender 105

will remain depressed until the obstacle or person is removed from contact with the fender, when it will return to its normal position. My fender is thus entirely automatic in its action when in operative position.

When not required for use, the fender may be slid back into the position indicated by dotted lines *a a* by first raising the stop 16 to permit the fender to be run into its inward or inoperative position. When pulled forward, the hook and stop serve to hold and lock the fender outwardly or in operative position.

I claim—

- 15 1. The combination of a vehicle-body, a pivoted carrier, a fender slidably mounted therein, and means to prevent other motion than a depression thereof automatically produced upon striking an obstacle.
- 20 2. The combination in a vehicle-fender, of a support, a fender having rearwardly-extended arms mounted on said support, and means connected therewith to prevent inward and upward motion of the fender end of said arms in any position in which they may be carried.
- 25 3. The combination in a vehicle-fender, of a support, fender-arms pivotally mounted intermediate their ends thereon, and means connected therewith for preventing inward and upward motion of the outer portions of said arms, permitting said fender to be depressed automatically upon striking an obstacle.
- 30 4. The combination in a vehicle-fender of a pivoted support, a fender slidably mounted thereon, and means to prevent other motion than a depression thereof automatically produced upon striking an obstacle.
- 35 5. The combination in a vehicle-fender, of a pivoted carrier, a fender slidably mounted therein, and a stop to prevent inward movement of the fender in said carrier in any position in which it may be carried.
- 40 6. The combination in a vehicle-fender, of a pivoted carrier, a fender having arms slidably mounted therein, and a stop to hold said fender in normal position, preventing its inward motion and causing impact with an obstacle to produce an automatic depression thereof.
- 45 7. The combination in a vehicle-fender, of a pivoted carrier, a fender slidably mounted therein, and means to prevent said fender from swinging upwardly when in operative position.
- 50 8. The combination in a vehicle-fender, of pivoted carriers, a fender normally carried in an outer position having arms slidably connected with said carriers and provided with a depending front, one or more rollers connected with said front adapted to run upon the rails or the ground when the fender is depressed, and one or more stops intermediate the carrier and said arms, to prevent inward

motion thereof and permit said fender being depressed automatically upon striking an obstacle.

9. The combination in a vehicle-fender, of hangers attached to a vehicle-body, a fender, means for pivotally connecting it with said hangers arranged for preventing other movement than a depression thereof, automatically produced upon striking an obstacle, and means acting automatically to restore said fender to normal position when said obstacle is removed.

10. The combination in a vehicle-fender, of hangers attached to the vehicle-body, a carrier pivoted thereto, a fender loosely mounted in said carrier and means to prevent either upward or inward swing of said fender and other than a depression thereof automatically produced upon striking an obstacle.

11. The combination in a vehicle-fender, of hangers attached to the vehicle-body, a cross-bar connected with said hangers, and a pivoted fender having hooks at its ends to engage said bar to prevent said fender from being lifted.

12. The combination in a vehicle-fender, of hangers attached to the vehicle-body, a cross-bar connected with said hangers, and a pivoted fender having hooked ends to engage said bar and a spring bearing upon said fender, the hooked ends and spring holding the fender in operative position.

13. The combination in a vehicle-fender, of a pivoted carrier, a fender having an arm slidably mounted in said carrier, and a stop-arm pivoted on said carrier bearing upon said arm to prevent inward movement of the fender in any position in which it is supported.

14. The combination in a vehicle-fender, of a pivoted carrier, a fender having an arm slidably mounted in said carrier, and a stop-arm pivoted on said carrier, to cause the free end thereof to bear against said arm to lock the latter against sliding inwardly in said carrier in any position in which it is supported.

15. The combination in a vehicle-fender, of supporting-arms, a carrier pivotally connected therewith, a fender-arm slidably mounted in said carrier, means on said arm for holding the fender in operative position, and means intermediate the carrier and fender-arm to prevent inward motion of said arm and to permit an automatic depression of the fender upon striking an obstacle.

16. The combination in a vehicle-fender, of a supporting-frame adapted to hold a fender in normal and in inoperative positions, and means for pivoting the fender thereon in normal position, to only permit it to be depressed, and means to hold the fender stationary in inoperative position.

17. A vehicle-fender comprising a pivoted carrier, a fender therefor arranged for automatic depression upon striking an obstacle,

- and means for elevating said fender after depression upon removal of said obstacle. 55
18. A vehicle-fender arranged for automatic depression upon striking an obstacle, 5 provided with means acting automatically for restoring it to normal position when said obstacle is removed and means to prevent raising the outer end of said fender when in said normal position. 15
19. A vehicle-fender provided with means normally supporting it in an exterior position and adapted to be automatically depressed by striking an obstacle and moved into a position to prevent said obstacle from passing under it when struck thereby, and means for restoring said fender automatically to normal position when said obstacle is removed. 20
20. A vehicle-fender provided with rollers to facilitate moving it forward into a series of positions in front of a vehicle, means to prevent moving it inwardly from said positions, and means for rendering the latter inoperative. 25
21. A vehicle-fender comprising pivoted and slideable fender-arms provided with means for normally supporting them in an exterior position to prevent other motion than a depression thereof, automatically produced upon striking an obstacle. 30
22. A movable vehicle-fender having side arms, a tilting carrier therefor having rollers to facilitate movement of said arms, yielding means for normally holding said fender elevated, and a stop to prevent movement of said arms in said carrier in any position in which it may be carried to permit only of depression of said fender produced automatically upon striking an obstacle. 35
23. The combination in a vehicle-fender, of a support, a fender having rearwardly-extended arms mounted on said support, and means connected therewith to prevent upward motion of the outer end of said arms in any position in which they may be carried. 40
24. The combination in a vehicle-fender, of a support, fender-arms pivotally mounted intermediate their ends thereon, and means connected therewith for preventing upward motion of the outer portions of said arms, permitting said fender to be depressed automatically upon striking an obstacle. 45
25. In a vehicle-fender, fender-arms pivotally intermediate their ends and arranged to be normally balanced in approximately horizontal position and means to prevent elevation of their outer ends and to permit of automatic depression upon striking an obstacle. 55
26. In a vehicle-fender, fender-arms pivotally intermediate their ends and arranged to be normally balanced in approximately horizontal position, means to prevent elevation of their outer ends and to permit of automatic depression upon striking an obstacle, and means to restore said fender to normal position. 60
27. In a vehicle-fender, the combination of hangers arranged to pivotally support a fender to permit the latter to swing longitudinally of said vehicle and means to prevent lifting or elevating the front end of said fender or other motion than a depression thereof, automatically produced upon striking an obstacle. 65
28. In a vehicle-fender, the combination of hangers arranged to pivotally support a fender to permit the latter to swing longitudinally of said vehicle, means to prevent lifting or elevating the front end of said fender or other motion than a depression thereof, automatically produced upon striking an obstacle, and means to restore it to normal position upon the removal of said obstacle. 70
29. In a vehicle-fender, inner and outer supports, a fender slidably mounted and normally maintained in approximately horizontal position thereon in inner or outer position, and means connected with said supports for permitting an automatic depression of said fender upon striking an obstacle. 75
30. In a vehicle-fender, inner and outer supports, a fender slidably mounted and normally maintained in approximately horizontal position thereon in inner or outer position, means connected with said supports for permitting an automatic depression of said fender upon striking an obstacle, and for restoring it to normal position upon removal of said obstacle. 80
- In testimony whereof I have signed my name to this specification in the presence of two subscribing witnesses. 90
